SLING AND METHOD OF MAKING SAME

Irvin R. Mitchell, St. Louis, Mo., assignor to A. Leschen & Sons Rope Company, St. Louis, Mo., a corporation of Missouri

Application March 9, 1946, Serial No. 653,395

5 Claims. (Cl. 87—8)

1

This invention relates to flexible slings, preferably of six members, or any reasonable multiple of three members, intended for use in hoisting or lowering heavy objects through the use of mechanical contrivances which are equipped with parts for receiving the eyes, or loops, of such slings.

One of the difficulties usually encountered in producing slings of this nature, which are generally formed of manila, hemp, or wire rope, is the tendency of the rope to twist while the sling is being formed. I overcome this tendency by forming the sling from a single length of material, which may comprise one or more pieces, which I manipulate in a novel manner to form the sling, instead of forming it in the manner common to rope slings heretofore made. Generally in braiding a sling a twist develops in the braided members, and in order to get the twist out it is necessary to so braid the members as to counteract the twisting tendency. I overcome this by weaving the sling from the center, through which I get more equal weaving without any twist, so that through my invention the material is woven in a manner not heretofore practiced in the art, which automatically eliminates the twisting tendency.

The present invention differs from other rope slings in the method of weaving, or braiding, or plaiting. It consists of manipulating a single length of material so as to form six members, which are separated into three groups, and when these have been manipulated into a certain position, the remainder of the operation is performed from the center in such manner as to weave both ends of the sling at the same time, and then the material is locked in this position by inserting a pin, and then unweaving the two free ends of the material to the sling center, locking them through the center where the pin has been placed, removing the pin, which served as a temporary locking element only, and re-weaving them back into the sling.

Another important advantage of my invention is that through its use the sling attains the form of a flexible, cohesive unit, and the capacity of the six members of material which form the sling is very little less than the aggregate capacity of six separate units of the material.

In the drawings—

Fig. 1 illustrates a single length of material coiled before the weaving of the sling is commenced.

Fig. 2 illustrates the separation of the members into pairs or groups.

2

Fig. 3 illustrates the beginning of the weaving process.

Figs. 4, 5, and 6 illustrate progressive steps in the weaving and locking of the braided members.

Fig. 7 illustrates the woven sling before the ends have been unbraided to approximately the center of the sling, and with a temporary locking pin inserted to prevent unweaving of the members.

Fig. 8 is a view similar to Fig. 7 with the free ends shown in their pass through the central portion of the sling to lock the woven members in position, replacing the temporary locking pin shown in the center of Fig. 7.

Fig. 9 illustrates the woven sling completed and one end spliced into the other end somewhat distant from the terminus thereof, with one end still unspliced into the sling.

Fig. 10 illustrates the completed sling.

The invention comprises a single length of material of a single unit or a number of units, having two free ends A and B. The first step in the manipulation of said material consists in coiling it to form six parallel members 1 to 6, respectively, with the free ends A and B extending beyond the same end of the coil, as illustrated in Fig. 1. While I have shown six unit members of the material to be woven or braided, any reasonable multiple of three can be employed. At this point the members 1 to 6, respectively, are separated to form three pairs, or groups, 7, 8, and 9, respectively, as illustrated in Fig. 2, with the free ends A and B preferably in the same pair, viz., pair 7.

From this point on the braiding, or weaving, is done by alternately crossing the side pairs over the center pair in hairbraid fashion, the beginning of which operation is illustrated in Fig. 3. This braiding or weaving operation is commenced by manipulating the members from the center of the sling, which causes both ends of the sling to be simultaneously braided or formed. This operation is clearly illustrated in enlarged detail in Figs. 3, 4, 5, and 6. In Fig. 3 the pair 8 drops down back of the pair 9. In Fig. 4 pair 7 drops down in front of pair 9, pair 9 now occupying the uppermost position, pair 7 the intermediate position, and pair 8 the lowermost position. In Fig. 5 pair 9 still remains in the uppermost position while pair 7 drops down back of pair 8, pair 8 now being the intermediate pair, and pair 7 being in the lowermost position.

In Fig. 6 pair 8 has been elevated to the uppermost position back of pair 9, which is now in

the intermediate position with pair 7 still in the lowermost position. The disclosed operations progressively continue until the braided portions 10 and 11 extend to the center of the sling body, as illustrated in Fig. 7, and as compact as may be desired by the operator, with the ends A and B preferably forming the center pair, and the portions 10 and 11 comprising a plurality of nodes 12 and preferably having end loops 13 and 14, respectively. At this point a temporary locking pin 16 is inserted to retain the woven members in position.

I proceed now to the locking of the sling, as follows: The free ends A and B are unbraided to a point just past the temporary locking pin 16, which is the longitudinal center 15 of the sling, their former paths in the woven sling upon withdrawal being marked by tracers (not shown), and re-inserted back through said center in such manner as to lock the weave in secure position. The preferred method of such locking is as follows: Both A and B form the center pair over the temporary locking pin 16 when the final weaving movement has been completed. The end A is looped around its adjacent outside pair and secures said outside pair, and then back into the portion 11 of the sling body, and rebraided back into its original path in said sling body, as marked by tracer (not shown). The end B is looped around its adjacent outside pair and secures said outside pair, and then back into the portion 11 of the sling body and rebraided back into its original path in said sling body, as marked by tracer (not shown).

The unbraiding and rebraiding of A and B as described have locked the sling braid at the center 15. It will be observed from Fig. 9 that at this time the ends A and B have led back to their original positions. The free ends A and B may now be secured in any one of various numbers of ways. The method illustrated in Figs. 9 and 10 is the preferred form. In a manner well understood in the art, the free end B is now spliced into the body of the end A, as shown in Fig. 9, and secured tightly in position, and the free end A is looped and inserted, or tucked, into the sling at the point where the sling body commences. The sling has now assumed the position shown in Fig. 10, preferably having the complete end loops 13 and 14.

From the above description it is obvious that my method of braiding avoids twisting and equalizes the tension in all members throughout all parts of the sling. The above described braiding can be done in such a manner that a flat braid is formed with the pairs of members side by side in a flat plane, or it may be done in such a way as to form a rolled edge in the braided sling body. The rolled edge method is preferred and is accomplished by folding over, or rolling over, each pair at the edge of the sling body as it is braided.

By having the locking section at the longitudinal center of the sling it is my belief that I thereby provide an equalizing section for absorbing all or any unequal strain or strains that might develop during the use of the sling.

I claim:

1. The method of forming integrally from a single length of material a flexible sling, which consists in coiling said length of material into a plurality of straight, parallel portions and connecting end sections, said coiling providing two free ends of the coiled material, grouping said

straight portions into three pairs, the two free ends being at the same end of the coil, braiding said three pairs together from the center, and unbraiding said two free ends to the center of the sling and re-inserting them back into the braided structure in such manner as to securely lock the braid, and returning said free ends back to the same end of the coil they occupied before they were unbraided.

2. The method of forming integrally from a single length of material a flexible sling, which consists in coiling said length of material into a plurality of straight, parallel portions and connecting end sections, said coiling providing two free ends of the coiled material, grouping said straight portions into three pairs, the two free ends being at the same end of the coil, braiding said three pairs together from the center, and unbraiding said two free ends to the center of the sling and re-inserting them back into the braided structure in such manner as to securely lock the braid, returning said free ends back to the same end of the coil they occupied before they were unbraided, and splicing said two free ends into the sling.

3. The method of forming integrally from a single length of material a flexible sling, which consists in coiling said length of material into a plurality of straight, parallel portions and connecting end sections, said coiling providing two free ends of the coiled material, grouping said straight portions into three pairs, the two free ends being at the same end of the coil, braiding said three pairs together from the center, and unbraiding said two free ends to the center of the sling and re-inserting them back into the braided structure in such manner as to securely lock the braid, returning said free ends back to the same end of the coil they occupied before they were unbraided, and providing a section at the center of the sling to equalize any unequal strains that might develop during the use of the sling.

4. The method of forming a flexible sling of a single length of material, which consists in grouping said material into six members and again dividing said members into three pairs with the free ends of said length of material extending beyond the same end of said sling, simultaneously interbraiding the three pairs of the sling, unbraiding the free end portions of said material approximately to the center of said sling, rebraiding said end portions back into said sling so as to lock the braid, and securing the free ends of said members.

5. A flexible braided sling comprising three groups of members interbraided and permanently locked at the sling center, and having two end portions terminating at one end of said sling, said two end portions passing about adjacent outside strands at the sling center so that each of said two end portions occupies the path originally occupied by it through half the length of the sling.
